L. A. SUBERS,
REINFORCED LAMINATED COHESIVE INTERWOUND FABRIC BAND,
APPLICATION FILED JUNE 18, 1912.

1,136,292.

Patented Apr. 20, 1915.

UNITED STATES PATENT OFFICE.

LAWRENCE A. SUBERS, OF CLEVELAND, OHIO.

REINFORCED LAMINATED COHESIVE INTERWOUND FABRIC BAND.

1,136,292.

Specification of Letters Patent. Patented Apr. 26, 1915.

Application filed June 18, 1912. Serial No. 704,411.

To all whom it may concern:

Be it known that I, LAWRENCE A. SUBERS, a citizen of the United States, and resident of Cleveland, in the county of Cuyahoga and State of Ohio, have invented certain new and useful Improvements in Reinforced Laminated Cohesive Interwound Fabric Bands, of which I hereby declare the following to be a full, clear, and exact description, such as will enable others skilled in the art to which it appertains to make and use the same.

The objects of the invention are to provide an improved form of fabric capable of being employed in the construction of high pressure hose or analogous tubing or as a protective layer in pneumatic tires and comprises a reinforced laminated-cohesive-interwound fabric composed of laminated-cohesive-interwound bands similar in construction to the bands described in my previously issued Letters Patent Nos. 1,024,040, 1,017,271 and 1,021,014 in which a full description of the character of the fabric is given.

In the present invention a ribbon or band of metal or other desired substance is inserted in the hollow fabric bands while the same are being constructed and they are afterward formed into a laminated-cohesive-interwound fabric.

This reinforcing element is formed of flexible and resistant material of light weight, such as thin sheet metal, and is employed to provide with the fabric bands a reinforced fabric in the manner hereinafter described, shown in the accompanying drawings and specifically pointed out in the claims.

In the accompanying drawings, Figure 1 is a horizontal section of a laminated band in which a reinforcing ribbon or band is inclosed; Fig. 2 is an enlarged transverse section of the fabric band showing a portion of the mandrel which guides the reinforcing ribbon; Fig. 3 is a greatly enlarged transverse section of the reinforced fabric band; Fig. 4 is an isometric view of series of crossed, reinforced, adhesive fabric bands of which the laminated fabric is composed before they have been compressed together in the manner described in my former patents to complete the two-ply laminations; Fig. 5 is a plan view of a portion of a sheet of fabric formed of reinforced fabric bands and showing a protected edge formed by binding thereover an adhesive band of tape or other desired material; Fig. 6 is a transverse sec-

tion of one edge thereof enlarged; Fig. 7 is an enlarged plan view of a fabric band broken away to show a modified form of the reinforcing element therein; Fig. 8 is a transverse section thereof; Fig. 9 is a plan view of a portion of a hose or analogous tubing showing several layers of fabric bands arranged to provide for a predetermined amount of tensile strength therein, each band containing a reinforcing element or strip.

In these views A is a tubular flattened band composed of laminations or layers formed as described in my previous patents by interwinding fibrous bands A', A' upon a mandrel.

B is a protective or reinforcing band or ribbon formed preferably of tough, light and flexible metal or other suitable material which may be fibrous or of fibrous origin which preferably passes through the hollow mandrel C on which the fabric band is constructed and which is inserted in the band A before flattening and compressing the same and which is caused to adhere thereto by the adhesive material M of the band.

As shown in Figs. 1, 2, and 3, holes B', B' may be made in the reinforcing element through which the adhesive material passes, and when vulcanized will tend to retain the reinforcing element in close contact with the interior of the surrounding fabric.

In Figs. 7 and 8 the surface of the reinforcing element is shown roughened at B', to provide a modified means of retaining the adhesive fabric band in close contact therewith.

The object in providing means causing the reinforcing element and fabric band to adhere closely together is to incorporate the parts together in as near a unitary structure as possible and prevent the reinforcing element from sliding or having any movement of any sort in the fabric band which would tend to open up or injure the integrity of the fabric band and fabric formed therefrom under excessive stress due to the rough usage which these or pneumatic tires receive in actual service.

In Figs. 4 and 5 a fabric E composed of the flattened fabric bands A is shown, all the bands being provided with reinforcing elements inserted therein.

In Figs. 5, 6 a flat sheet E of fabric is illustrated which may be made of any desired width and length for use as a protec-

tive layer inserted in a pneumatic tire and the edges are provided with a bead of rubber D or other suitable material and are also bound with bands F of tape or other desired material to prevent fraying or separation of the fabric bands and to avoid chafing of the reinforcing element against the adjacent fabric layers.

When vulcanized the fabric and binding 10 become practically a unitary structure.

The fabric formed of reinforced bands can be made to vary in expansibility by varying the angles at which the bands cross each other and their relative angular positions 15 relatively to the axis of the tube or tire in which they are laid.

Modifications in the shape or construction of the reinforcing bands can also be made and lie within the scope of the claims.

20 The reinforced fabric as described when used in a tire casing renders an efficient protection to the tread surface or side and other outside surfaces of the tire or inner tube and tends to prevent abrasion, cutting or 25 puncturing of the casing to a sufficient depth to injure the inner tube.

A hose pipe as shown in Fig. 9 can be completely constructed of reinforced bands or as many layers of reinforced bands can 30 be employed as may be desired.

Having described the invention what I claim as new and desire to secure by Letters Patent is:

1. As an article of manufacture, a band 35 for incorporation in a fabric, comprising a flattened tube composed of unwoven interwound groups of close lying parallel yarns or threads arranged in parallel rows and the sides of the tube compressed together to 40 form selvage edges, the said band saturated with adhesive material, and a reinforcing band inclosed therein, the edges of which are parallel to said selvage edges.

2. As an article of manufacture, a band

for incorporation in a fabric, comprising a 45 flattened tube composed of unwoven interwound groups of close lying parallel yarns or threads arranged in parallel rows and the sides of the tube compressed together to 50 form selvage edges, said band saturated with adhesive material, and a reinforcing band inserted therein said adhesive material preventing movement of said reinforcing band in said fabric band.

3. A band for incorporation in a fabric 55 comprising a tubular structure composed of threads formed from groups of close lying parallel yarns or threads, said groups of threads laid in spaced parallel rows at predetermined angles crossed by spaced groups 60 laid at predetermined angles thereto, a row of said spaced groups of threads filling the spaces between the rows of groups of threads parallel therewith, the sides of said tube being flattened together and saturated 65 with adhesive material, an exterior coating on said band and a reinforcing band inserted in said flattened tube, said reinforcing band provided with irregularities of 70 surface, said adhesive material engaging said irregularities of surface.

4. In a constituent element for an interwound fabric in which the elements cohere together and are interlaid a flattened tube 75 composed of unwoven threads, interwound and interlaid with each other, each thread composed of a parallel series of yarns, the finished product saturated with adhesive material, and provided with an external coating of the same, and a flat band of reinforcing material inclosed in said flattened tube.

In testimony whereof, I hereunto set my hand this 7th day of June 1912.

LAWRENCE A. SUBERS.
